UNITED STATES PATENT OFFICE.

HENRY THOMAS WILEY, OF CAKE, OREGON.

ORE MILL AND THE LIKE.

1,404,560.

Specification of Letters Patent. Patented Jan. 24, 1922.

Application filed October 4, 1919. Serial No. 328,453.

To all whom it may concern:

Be it known that I, HENRY THOMAS WILEY, a citizen of the United States, and a resident of Cake, in the county of Malheur 5 and State of Oregon, have invented certain new and useful Improvements in Ore Mills and the like, of which the following is a specification.

This invention relates to an improvement 10 in ore mills, seed and grain mills and the like, and one of the principal objects of my invention is to provide an improved mill which may be used for various purposes, such as crushing quartz, or grinding grain, 15 the construction being such that only slight variations in construction are necessary to adapt the mill to various uses.

A further object of the invention is to provide an improved mill in which the crushing 20 process is accomplished by the operation of a gravity actuated crushing member arranged inside of a vertical rotating wheel carrying inclined plates against which the crushing member operates.

25 A further object of the invention is to provide an improved mill of the class described, which will be extremely simple, durable, efficient in operation and inexpensive to manufacture.

30 With these and other objects in view which will become apparent as the description proceeds, the invention resides in the construction, combination and arrangement of parts hereinafter more fully described and claimed,

35 and illustrated in the accompanying drawings in which like characters of reference indicate like parts throughout the several figures of which:

Figure 1 represents an elevational view of 40 an ore mill constructed on the principles involved in my invention;

Figure 2 represents an elevational view of the screen for regulating the size of the ore discharged;

45 Figure 3 represents a side elevational view of the drum and associated parts;

Figure 4 represents a fragmentary view enlarged, one side of the drum having been removed, showing the construction of crushing member;

Figure 5 represents a similar view, the crushing member being shown in section and the construction being that used in a grain mill;

50 Figure 6 represents a sectional perspective view taken on the line 6—6 of Figure 5; and

Figure 7 represents a fragmentary view showing in side elevation the drum of the grain mill shown in Figures 5 and 6.

Figure 8 is a view showing in edge elevation and somewhat diagrammatic the ore mill shown in the preceding views.

Referring more particularly to Figures 1 to 4 of the drawings, I provide a drum having a peripheral wall 1, and annular 65 side walls 2. A shaft 3 extends axially through the drum, and may be driven from a power pulley 4.

Spokes 5 mounted at their inner ends on a hub 6 fixed to the shaft carry the drum, 70 whereby the latter will be rotated with the shaft.

Against the inner side of the peripheral wall 1 is arranged end to end, a series of plates 7 each of which is substantially of 75 a wedge shape, having a flat upper surface 8, a narrowed end 9, and a relatively wide end 10. The plates are arranged as indicated in Figure 4 end to end, the narrow ends of the plates resting in under cut shoulders 11 provided in the large ends of the adjacent plates. The flat surfaces 8 of the plates, thus lie in planes which are set at an angle one with respect to the other around the periphery of the drum. Set 80 screws or bolts, or similar fastening devices 12 passing through the side walls of the drum and through the larger ends of the plates, retain the latter against displacement. 90

The crushing member includes a pair of rollers 13 retained in relative position one with respect to the other, and held by the action of gravity down against the crushing surfaces 8, by means of a weight 14 arranged in parallel relation with the rollers and carrying frames 15 which are hinged as at 16 to lateral ears projecting from the upper portion of the weight. Each of these frames is in the form of a pair of arms, 100 connected by pins 17 arranged in parallel relation with the rollers 13. Each of the pins 17 has a guide roller 18 rotatably mounted thereon. Cross arms 19 fixed to the ends of the weight 14, project to either 105 side thereof and carry pins 20 on which additional guide rollers 21 are mounted. It will thus be seen that each of the crushing rollers 13 is retained in place by means of the guide rollers 18 and 21, these guide rollers being arranged in a series around the upper surface of the crushing rollers. 110

The weight is rounded at its lower face as at 22, and this rounded surface assists the rollers 13 in the crushing process. Channels 23 provided in the side walls of the weight serve to receive the guide rollers 21.

The action of gravity tends to maintain the weight and the rollers always at the lower point of the drum, and hence as the 10 latter rotates, the crushing surfaces pass beneath the weight and rollers, and the result is that the weight together with the rollers pass across the surfaces 8 of the plates, thus crushing any material which 15 may be deposited thereon.

It will be noted from Figure 4 that the lines of contact between the rollers and the weight and the crushing surfaces 8, occur at analogous points with respect to the crushing surfaces, and hence the rollers and weight will move uniformly up the inclined surfaces as the drum rotates, and will drop together from one surface to the other, as will be readily understood.

25 A conical flange 24 arranged on one side of the drum, acts as an intake to the mill, and a similar flange 25 arranged on the opposite side acts as a discharge, the water and ore being fed to the drum through a 30 pipe and chute 26 and 27 respectively.

In order to regulate the size of the ore discharged I suspend an arcuate screen 28 of desired mesh, from the shaft 3, by means of a ring 29 within which the shaft rotates, 35 and which is connected by a link 30 with the converging arms 31 supporting the screen. The action of gravity will retain the screen suspended against the inner edge of the discharge funnel 25, as indicated in 40 Figure 3, at the lower point of this discharge funnel. The ore being discharged from the mill, will endeavor to flow from the mill at the lowest point of the latter and hence must pass through the screen in 45 seeking its exit. Any ore which is too large to pass through the screen will be retained in the mill until it is ground to a fine enough size to find a ready passage through the meshes of the screen.

50 Referring to Figures 5, 6 and 7, I have here shown a modified form of a mill which is particularly adapted for the grinding of grain and for separating the meal from the bran and for discharging the same separately from the drum 1^a.

As shown in Figure 7, the side corresponding to the discharge side of the drum 1^a is closed by a solid wall 2^a so as to prevent the discharge of the grain therefrom as in the 60 first form of my invention. The drum 1^a is provided exteriorly thereof with a continuous peripheral channel or trough 32 which is formed at regularly spaced intervals with discharge spouts L and L' arranged in pairs, as illustrated to advantage

in Fig. 8, the spouts L and L' of each pair extend in opposite directions from the periphery of the frame 1^a so that when the drum rotates, the discharge ends of the spouts are moved in different pairs. In the 70 present instance I have shown the peripheral channel 32 divided into four separate and distinct sections, adjacent sections being separated at their confronting ends by the discharge spouts L and L'. Arranged within the drum 1^a and adjacent 75 the channel 32 are separating screens S. The screens S correspond in length to the sections of the channel 32, and, as shown in Figures 5 and 7, each screen S having one 80 of its ends overlying the spout L' and connected to a partition 33 between adjacent spouts L and L'. The other end of each screen S is connected to a partition 34 disposed adjacent the spout L, and is flared 85 inwardly as at 35 to prevent the depositing of the grain into the spout L.

As in the first form of my invention I provide an annular series of plates 7^a, such plates in the present instance being provided 90 with openings 36 adjacent their smaller ends and across which screens 38 are placed.

The crushing device can be of the same construction as that used in the ore mills, 95 and as the grain is ground upon the inner surfaces of the plates 7^a it falls through the screens 38 onto the screens S and from there to the channel 32.

With the drum 1^a rotating in the direction 100 of the arrow in Figure 7, the grain which percolates through any one of the openings 36 falls onto the adjacent screens S, and as all of the screens S rotate with the drum, it will be clear that the ground grain upon 105 falling onto the screen will be precipitated toward the lower end thereof. The mesh of each screen S is such that only the meal percolates therethrough, while the bran remains upon its inner surface and is ultimately discharged through the discharge 110 spout L. The meal in passing through the screen S falls into the trough 32 and is discharged through the adjacent spout L'. It will be understood that the partitions 33 and 115 34 prevent retrograde movement of the ground grain during the rotation of the drum, so that with the drum rotating continuously in a clock-wise direction the meal and bran will be discharged successively 120 throughout the several spouts L and L'. By virtue of the fact that the discharge ends of spouts L and L' move in different planes it will be clear that the bran discharged from the spout L will not mingle with the 125 meal discharged from the spout L', so that a separate collection of the two is rendered possible.

Although I have herein shown and described only two forms of mills embodying 130

my invention, it will be understood that various changes and modifications may be made without departing from the spirit of the invention and the spirit and scope of the claims.

5 I claim:—

1. A mill comprising a vertically arranged rotating drum, a plurality of plates arranged against the peripheral wall of the drum end to end and having upper crushing surfaces arranged in various planes with respect to each other, a pair of rollers arranged within the drum and adapted to roll against the surfaces of the plates, a weight 10 arranged between the rollers, and having a surface adapted to move across and contact with the surface of the plates, and guide rollers carried by the weight for retaining the first said rollers in position relatively 15 to each other.

2. In a mill, a vertically arranged rotating drum, a plurality of substantially wedge shaped plates arranged end to end around the peripheral wall of the drum, the upper 25 surfaces of said plates being arranged in various planes with respect to each other, and gravity actuated rollers arranged in the drum transversely therein and adapted to roll across and contact with the upper 30 surfaces of the plates.

3. A gravity actuated crushing member for use in connection with mills, comprising a pair of spaced rollers, a weight arranged between the rollers, brackets hinged to the 35 weight and over lying the rollers, and rollers carried by the brackets and engaging with the first said rollers, and additional guide rollers carried by the weight and likewise engaging the first said rollers.

4. A gravity actuated crushing member 40 for mills, including a pair of spaced rollers, a weight arranged between the rollers, and guide rollers carried by the weight and engaging the first said rollers, for retaining them in predisposed position with respect 45 to each other, substantially as described.

5. A crushing member for mills including a plurality of crushing rollers, a weight,

and means connected with the weight on opposite sides thereof for maintaining the 50 crushing rollers in predisposed position with respect to each other.

6. A mill comprising a rotatable drum formed on its periphery with discharge spouts arranged in pairs about the periphery of said drum, a circular series of plates within said drum, grinding means associated with said plates, means for directing part of the ground material to said spouts, and means for separating the fine material 60 from the coarse part thereof and for discharging the same separately through said spouts.

7. A grinding mill comprising a rotatable drum, stationary grinding means within 65 the drum, a plurality of plates within said drum having screened openings formed therein, and a plurality of screens within said drum arranged to discharge the coarse and the fine parts of the ground material 70 from said opening separately through the periphery of said drum.

8. A grinding mill comprising a rotatable drum, stationary grinding means within the drum, a plurality of plates within said 75 drum having screened openings formed therein, a plurality of screens within said drum arranged to discharge the coarse part of the ground material from said openings through the periphery of said drum, and a 80 trough arranged to receive and deposit the fine part of the ground material exteriorly of the drum and separately from the coarse material.

9. A mill comprising a rotatable drum 85 having inlet and outlet openings formed in the opposite sides thereof, a shaft extending through said openings and operatively connected to said drum, grinding means within the drum, and a segmental 90 screen swingingly supported on said shaft, said screen normally occupying a vertical position and screening a portion of the outlet opening for the purpose described.

HENRY THOMAS WILEY.
